JOHN L. SMITH.

UNITED STATES PATENT OFFICE.

JOHN BRYANT, OF SAN FRANCISCO, CALIFORNIA.

DESIGN FOR A SUMMER FRONT FOR A FIRE-PLACE GRATE.

Specification forming part of Design No. 5,734, dated April 2, 1872.

SPECIFICATION.

To all whom it may concern:

Be it known that I, JOHN BRYANT, of the city and county of San Francisco, State of California, have invented a new and useful Design for Summer Pieces for Grates; and I do hereby declare that the following is a full and exact description of the same, reference being had to the accompanying drawing and to the letters marked thereon.

My invention relates to a new design for summer pieces or screens for grates; and the nature of the design is fully represented in the accompanying photographic illustration, to which reference is made.

A is the outside frame or border, which is made to conform to the shape of the grate-opening, and within this border my ornamental design is constructed. It consists, mainly, of a series of concentric oval figures near the top, and an ornamented open scroll-work beneath. The outer oval B is a plain molding, within which is an oval, C, formed of two vines, twisted together, as shown. The next oval, D, is raised

somewhat, and has a series of semi-globular or acorn-shaped protuberances rising from an ornamental ground extending entirely around it. The fourth oval, E, consists of an open-work design, as shown; while the fifth oval, F, is a plain molding, and surrounds a central plain ground, J, so that the general effect of this portion of the design may be likened to an elaborate oval picture-frame. The central figure at the bottom of the screen is an ornamental star, G, and upon each side of this star is an open scroll-work, H. The bottom of the border A is slightly arched, and may be plain or ornamented with acorns I, as shown.

Having thus described my design, I claim and desire to secure by patent—

A design for summer pieces for grates, substantially as herein set forth.

In witness whereof I have hereunto set my hand.

JOHN BRYANT.

Witnesses:

GEO. H. STRONG,

JOHN L. SMITH.
